Application May 4, 1953, Serial No. 24,823

Term of patent 14 years

(Cl. D74—9)

To all whom it may concern:

Be it known that I, Albert W. Lindberg, Jr., a citizen of the United States, residing in Bayonne, in the county of Hudson, State of New Jersey, have invented a new, original, and ornamental Design for a Mail Box, of which the following is a specification, reference being had to the accompanying drawing, forming a part hereof, in which:

Fig. 1 is a top plan view of a mail box, embodying my new design;

Fig. 2 is a front elevation thereof;

Fig. 3 is an elevation of the right hand end of the mail box;

Fig. 4 is a bottom plan view thereof.

The essential features of my design reside in the portions shown in solid lines on the drawing.

I claim:

The ornamental design for a mail box, as shown and described.

ALBERT W. LINDBERG, JR.
